UNITED STATES PATENT OFFICE.

WILLIAM H. McALLISTER, OF NEWBERRY, PENNSYLVANIA.

CASTER.

1,162,627.

Specification of Letters Patent.

Patented Nov. 30, 1915.

Application filed April 14, 1915. Serial No. 21,445.

To all whom it may concern:

Be it known that I, WILLIAM H. McALLISTER, a citizen of the United States, residing at Newberry, in the county of Lycoming and State of Pennsylvania, have invented certain new and useful Improvements in Casters; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in casters and consists in the provision of a simple and efficient means whereby the caster may be held at different elevations, being held in an adjusted position by friction means.

The invention comprises various details of construction, combinations and arrangements of parts which will be hereinafter fully described, shown in the accompanying drawings and then specifically defined in the appended claims.

My invention is illustrated in the accompanying drawings, in which:

Figure 1 is a side elevation of a caster. Fig. 2 is a vertical sectional view through the same. Fig. 3 is an edge view. Fig. 4 is a section on line 5—5 of Fig. 1. Fig. 5 is a detail perspective view of a part of the invention, and Fig. 6 is a detail view of a modification.

Reference now being had to the details of the drawings by letter, A designates the object to which the caster is fastened by means of screws A', said screws engaging 40 and holding the plate B in place and which has a circular outlined rib B' thereon and a central conical-shaped flange B² adapted to receive the beveled head C of the swivel bolt D, which latter is shouldered as at D' and upon which shoulder the washer E rests which is so shaped as to form raceways for the balls F and the cylindrical bearings G which rest upon the horizontally disposed portion H of the casing H' having oppositely disposed walls which are slotted as at H² leaving narrow resilient strips H³ which are allowed to yield a little under pressure in a manner to be presently de-

scribed for the purpose of holding the caster at different elevations.

Said swiveled bolt passes through an opening in the member H and a washer C² is mounted upon the bolt and held by the head C³ thereof against the under surface of the laterally projecting portion K of the bracket member K', which latter has its lower end K² bent at an angle and extending underneath the bottom of the casing H'. Plates, designated by Letters L and N, one of which is shown in Fig. 6, are provided 65 with lugs O projecting from the ends thereof and which serve as supports for the plates by their resting upon the upper edges of the yoke Q which supports the spindle R of the caster wheel S. Said plates, it will 70 be noted upon reference to Fig. 2, are positioned one upon either side of the bracket member K' and serve as frictional clamping plates for engagement with the same to hold the yoke Q in different positions.

A lug T projects from the yoke and forms a convenient means whereby the yoke may be raised slightly by the foot of a person when it is desired to adjust the caster, the adjustment being permitted by raising the 80 rear end of the yoke to allow the plates L and N to frictionally disengage the bracket member K'. A roller W is mounted upon a pin W' and is frictionally in contact with one end of the casing H' and at 85 the lower end of the face engaged by said roller is a projection H², forming a stop to limit the movement of the yoke in one direction.

In Fig. 6 of the drawings, I have shown 90 a slight modification of the member holding the raceway J, consisting of a plate J' having a hollow conical-shaped boss J² for the reception of the swiveled member J³ which takes the place of the swiveled bolt 95 shown in Fig. 2 of the drawings.

In operation, when it is desired to adjust the yoke carrying the caster to different elevations, it may be done by the operator raising upon the lug T which will throw the 100 yoke away from the friction engaging plates N and L, thus allowing the yoke to be elevated as may be desired and, after pressure is relieved from the lug T, the yoke will be held by the lower marginal edge 105 thereof frictionally engaging the plate L,

throwing the weight of the caster against the friction plates and the roller W. When the caster is adjusted to any particular position, it may be operated in the usual manner as other casters.

What I claim to be new is:—

1. A caster comprising a swiveled casing and a resilient bracket mounted thereon, a yoke with a caster wheel journaled therein, and friction means coöperating with the resilient bracket member for holding the yoke in different positions.
2. A caster comprising a casing and a swiveled support for the same, a resilient bracket member mounted in the casing and spaced apart therefrom, a caster carrying yoke movable about said casing, plates engaging said bracket and against which the yoke is adapted to bear, and a roller carried by the yoke, coöperating with the plates to hold the yoke in adjusted position.
3. A caster comprising a casing and a swiveled support for the same, a resilient bracket member mounted in the casing and spaced apart therefrom, a caster carrying yoke movable about said casing, plates engaging said bracket and against which the yoke is adapted to bear, a roller carried by the yoke, coöperating with the plates to hold the yoke in adjusted position, and a projection upon the casing to limit the movement of the yoke in one direction.
4. A caster comprising a casing and a swiveled support for the same, said casing having slots therein forming resilient strips, a resilient bracket member connected to the casing, a plate between said strips and said bracket, a caster carrying yoke, and a friction plate interposed between the same and said resilient bracket, and an anti-friction roller carried by the yoke and against which the edge of the casing is adapted to bear.
5. A caster comprising a casing and a swiveled support for the same, said casing having slots therein forming resilient strips, a resilient bracket member connected to the casing, a plate between said strips and said bracket, a caster carrying yoke, a friction plate interposed between the same and said resilient bracket, an anti-friction roller carried by the yoke and against which the edge of the casing is adapted to bear, and a projection upon the yoke serving as a means for throwing the same out of frictional contact with said plate.
6. A caster comprising a casing having a

transverse apertured portion and swivel mounting therefor, said yoke having slots in the walls thereof forming a resilient strip, an angled resilient bracket member mounted upon the casing and spaced apart from said strips, the lower end of the bracket member being angled, a caster carrying yoke movable about the casing, plates mounted one between the resilient strip and bracket member and the other intermediate the latter and the yoke which bears frictionally against the same, and an anti-friction wheel mounted upon the yoke and bearing against the opposite side of the casing.

7. A caster comprising a casing having a transverse apertured portion and swivel mounting therefor, said yoke having slots in the walls thereof forming a resilient strip, an angled resilient bracket member mounted upon the casing and spaced apart from said strips, the lower end of the bracket member being angled, a caster carrying yoke movable about the casing, plates mounted one between the resilient strip and bracket member and the other intermediate the latter and the yoke which bears frictionally against the same, an anti-friction wheel mounted upon the yoke and bearing against the opposite side of the casing, and means for limiting the movement of the yoke in one direction.

8. A caster comprising a casing having a transverse apertured portion and swivel mounting therefor, said yoke having slots in the walls thereof forming a resilient strip, an angled resilient bracket member mounted upon the casing and spaced apart from said strips, the lower end of the bracket member being angled, a caster carrying yoke movable about the casing, plates mounted one between the resilient strip and bracket member and the other intermediate the latter and the yoke which bears frictionally against the same, an anti-friction wheel mounted upon the yoke and bearing against the opposite side of the casing, means for limiting the movement of the yoke in one direction, and a lug projecting from the yoke forming means for raising the same out of frictional engagement with the adjacent plate.

In testimony whereof I hereunto affix my signature in presence of two witnesses.

WILLIAM H. McALLISTER.
